WILLIAM WILSON, JR., OF RAYMOND, ILLINOIS.

Letters Patent No. 92,553, dated July 13, 1869.

IMPROVEMENT IN PORTABLE FIELD-FENCE.

The Schedule referred to in these Letters Patent and making part of the same.

To all whom it may concern:

Be it known that I, WILLIAM WILSON, Jr., of Raymond, in the county of Champaign, and State of Illinois, have invented a new and useful Improvement in Portable Field-Fences and Gate combined; and I do hereby declare that the following is a full, clear, and exact description thereof, which will enable others skilled in the art to make and use the same, reference being had to the accompanying drawings, forming part of this specification, in which—

Figure 1 is a vertical cross-section of my improved fence, taken through the line $x\ x$, fig. 2.

Figure 2 is a side view of a portion of the same.

Figure 3 is a top view of a portion of the same, partly in section, through the line $y\ y$ of fig. 2.

Figure 4 is a detail view of the latch and latch-board.

Figure 5 is a detail view of a hinged coupling-board.

Similar letters of reference indicate corresponding parts.

My invention has for its object to furnish a simple, cheap, strong, durable, and substantial fence, and one which shall be so constructed and arranged that any of the panels may be easily adjusted for use as a gate; and

It consists in the construction and combination of the various parts of the fence, as hereinafter more fully described.

The panels, coupling-boards, braces, latch-board, and latch, are all made of the same-sized stuff, preferably about four inches in breadth.

A are the panels, which are formed by attaching vertical slats, a^1 , to the ends of the horizontal bars a^2 .

The horizontal bars or slats a^2 may be of any desired length, and, when long, the panels A may be strengthened by one or more intermediate vertical slats or bars a^3 , as shown in fig. 2.

The panels A may be formed with three, four, five, or other desired number of horizontal bars a^2 , as the circumstances of the case may require.

B are the coupling-boards, by means of which the adjacent ends of the panels A are coupled or connected to each other.

The coupling-boards B are secured to the panels A by pins C, passed through holes in the end of the said coupling-boards B, and through holes in the vertical end bars a^1 of the panels A, where they are secured in place by keys D and E, passed through the ends of the said pins C, upon each side of the fence.

The keys D are permanently attached to the pins C, so as to serve as heads to said pins.

The other keys, E, are detachable, so that they may be removed, when desired, for convenience in taking down and removing the fence.

The coupling-boards B may be grooved transversely to receive the keys, as shown in fig. 5.

If desired, the detachable keys E may be connected by small chains with the permanent keys D, so that they may not be accidentally lost.

G are the supporting-braces, which are made in the shape and manner shown in fig. 1.

The braces G are notched in their upper angle to receive and fit upon the upper edge of the upper coupling-bar B, and they are also notched in the centre of the upper edge of the cross or base-bar g' , to fit upon the lower edge of the lower coupling-board B, as shown in figs. 1 and 2.

By this construction, the fence is supported by the braces G, the angling position of the inclined side bars of said braces forming a broad and firm base for the fence.

At the angles of the fence, and where it is desired to use one of the panels A as a gate, the coupling-bars C are hinged, as shown in fig. 5.

When one of the panels A is to be used as a gate, the hinged bars B are substituted for the rigid bars upon one end only of the panel, the opposite end being detached from its panel, which latter is provided with the latch and its bar in place of the rigid bars B, and vertical strips a^1 .

The gate-panel will now swing upon its hinges, and be held closed, when desired, by the latch-bar fitting over one or the other of the central horizontal boards a^2 of the gate.

Having thus described my invention,

I claim as new, and desire to secure by Letters Patent—

1. An improved portable fence, formed by the combination of the panels A, supporting-braces G, coupling-boards B, whether rigid or hinged, pins C, and keys D and E, with each other, said parts being constructed and arranged substantially as herein shown and described, and for the purposes set forth.

2. The fence, when any desired panel is adapted to be converted into a gate by means of the hinged coupling-bars B, latch-board I, catch H, pins C, and keys D and E, substantially in the manner herein shown and described.

WILLIAM WILSON, JR.
